(57) **CLAIM**

The ornamental design for a dual linear polarization conical horn antenna, as shown and described.

DESCRIPTION

FIG. 1 is a perspective view of a dual linear polarization conical horn antenna design showing my new design.

FIG. 2 is a front view of a dual linear polarization conical horn antenna.

FIG. 3 is a rear view of a dual linear polarization conical horn antenna.

FIG. 4 is a right side view of a dual linear polarization conical horn antenna.

FIG. 5 is a left side view of a dual linear polarization conical horn antenna.

FIG. 6 is a top view of a dual linear polarization conical horn antenna; and,

FIG. 7 is a bottom view of a dual linear polarization conical horn antenna.

Any shading and cross-hatching are not features of the design but are utilized to illustrate the surface contours of the dual linear polarization conical horn antenna design in the drawings.

The broken lines depict portions of the dual linear polarization conical horn antenna that form no part of the claimed design.
